UNITED STATES PATENT OFFICE.

JOHN LEWIS MCKAY, OF CHICAGO, ILLINOIS.

DESIGN FOR A SPOON-HOLDER.

SPECIFICATION forming part of Design No. 31,665, dated October 17, 1899.

Application filed September 15, 1899. Serial No. 730,637. Term of patent 7 years.

To all whom it may concern:

Be it known that I, JOHN LEWIS MCKAY, a citizen of the United States, residing at Chicago, in the county of Cook and State of Illinois, have invented and produced a new and original Design for a Spoon-Holder, of which the following is a specification.

In the accompanying drawings, forming a part of this specification, Figure 1 is a perspective view of the spoon-holder. Fig. 2 is a side or edge elevation of the same. Fig. 3 is a detail cross-section through the portion of the spoon-holder which is designed to receive the handle or shank of the spoon.

Similar numerals of reference designate corresponding parts in the different figures of the drawings.

The leading or material feature of the design consists of a series of dish-engaging fingers 1 and 2. These fingers, of which the central one is designated by the numeral 1 and the other ones at each side thereof indicated by the numeral 2, lie in different planes. The fingers 2 are substantially straight, except as to their extremities, which are deflected slightly to one side, as shown at 3. The intermediate or central finger 1 is deflected at its point of junction 4 with the body of the holder, and a U-shaped bend 5 is given to said finger. At the point 6 the intermediate finger is again bent and curved in the reverse direction to form a terminal portion 7, which is described on a greater arc than the U-shaped portion above referred to.

The said terminal portion is also curved so as to diverge from the corresponding terminal portions of the fingers 2.

Another leading feature of the design consists in the formation of the spoon-receiving portion of the holder, which comprises a base 40 or rest 8, the opposite side edges of which are bent or curved inward toward each other, as shown at 9, and again bent or recurred in the opposite direction, as shown at 10, and thence extended in oblique relation to the 45 base, thereby forming a flaring entrance to the space which is provided for the passage of the spoon-handle. This passage (shown at 11) is of a width slightly greater than the narrowest portion of the spoon-handle and 50 is designed to receive and permit of the passage of the spoon-handle without canting or turning the handle. The spoon-receiving portion sets at an obtuse angle to the plane of the fingers 1 and 2.

Having described my invention, what I claim as new, and desire to secure by Letters Patent, is—

The design for a spoon-holder, as herein shown and described. 60

In testimony that I claim the foregoing as my own I have hereto affixed my signature in the presence of two witnesses.

JOHN LEWIS MCKAY.
